US00D896591S

(12) **United States Design Patent** (10) **Patent No.:** **US D896,591 S**
Seiders et al. (45) **Date of Patent:** **** Sep. 22, 2020**

(54) **INSULATING DEVICE**(71) Applicant: **YETI Coolers, LLC**, Austin, TX (US)(72) Inventors: **Roy Joseph Seiders**, Rollingwood, TX (US); **Derek G. Sullivan**, Austin, TX (US); **Erik Steven Larson**, Austin, TX (US); **Alex Baires**, Austin, TX (US)(73) Assignee: **YETI Coolers, LLC**, Austin, TX (US)(***) Term: **15 Years**(21) Appl. No.: **29/703,095**(22) Filed: **Aug. 23, 2019****Related U.S. Application Data**

(63) Continuation of application No. 29/624,126, filed on Oct. 30, 2017, now Pat. No. Des. 862,177, which is a continuation of application No. 29/553,995, filed on Feb. 5, 2016, now Pat. No. Des. 801,123.

(Continued)

Primary Examiner — Terry A Wallace(74) *Attorney, Agent, or Firm* — Banner & Witcoff, Ltd.(57) **CLAIM**

The ornamental design for an insulating device, as shown and described.

DESCRIPTION

FIG. 1 is a top, front, left perspective view of an insulating device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dot-dash lines represent unclaimed boundaries. The zig-zag broken lines represent zipper teeth and form no part of the claimed design. The even-length broken lines form no part of the claimed design.
